ELECTRIC LAMP

Frank N. Mariani, New York, N. Y.

Application February 26, 1938, Serial No. 192,751

5 Claims. (Cl. 240—81)

The invention relates to lamps generally and particularly is concerned with a table lamp and an object of the invention is realized in the provision of a novel and improved lamp wherein a 5 rotatable and exterior article supporting member is utilized to conveniently conceal a switch for controlling the table lamp. Other objects, advantages, and features of the invention will be better understood from the following detailed 10 specification considered in connection with the accompanying drawing in which:

Fig. 1 is a perspective view of an electric lamp embodying the invention.

Fig. 2 is a bottom plan view, partly broken 15 away, of the lamp shown in Fig. 1.

Fig. 3 is a fragmentary view of the lamp, partly in elevation and partly in section, the sectional portion being taken on line 3—3 of Fig. 2.

Fig. 3^a is a sectional view taken on the line 20 3^a—3^a of Fig. 3 and

Fig. 4 is a fragmentary vertical section of the lamp base with rotatable cover or top.

Referring to the drawing for a more detailed description thereof, the numeral 1 indicates the 25 lamp in its entirety as shown in Fig. 1. Said lamp comprises a stationary housing having a circular hollow base 8, the bottom of which is a spider 9 comprising a circular central plate 10 and radial arms 11 integral with and extending therefrom 30 and connected to the rim of the base.

The stationary base 8 has an annular rotatable table or top 12 mounted on ball bearings 13 held in a raceway formed in the rim of the base, as shown in detail in Fig. 4, and said table or cover 35 12 has a central depressed annular shoulder or flange 12^b.

The shade 15 is mounted on a lamp fitted into a socket 16 which is secured to a tubular standard 17 to the lower end of which is threadably secured 40 a dome shaped member 18, as shown in Fig. 3. The dome shaped member 18 rests on the annular flange 12^b which constitutes a seat. A pair of internally threaded opposed studs or lugs 19 depend from the bottom face of the hemispherical member 18 and these studs fit into opposed sockets 21 which rise from the central plate 10 of the spider 9 and screw means 22 pass through the plate 10, part way through the sockets 21 and threadably engage the internally 45 threaded lugs 19 to secure the dome to the base. A lug 25 also depends from the hemispherical member 18 and rests on the plate 10. Opposed to the lug 25 is a block 26 which also depends from the hemispherical member 18 and rests on the 50 central plate 10 of the spider. 55

Block 26 constitutes a bearing having bore 26^a rotatably guiding a rotary electric make-and-break switch generally denoted 29. This type of switch is well known in the art and its structure is therefore not herein shown and described in 5 detail. This rotary switch however includes a knurled wheel or pinion 30 which is continuously engaged by an annular or crown gear 31 depending from annular shoulder or flange 12^b. Thus by turning table 12, either clockwise or counter-clockwise, the annular gear 31 is rotated and consequently, pinion 30 is rotated to either make or break the lamp circuit characterized in part by wires in the cable 35 connected thereto. The cover 12, being mounted on ball bearings moves 10 easily and thus the cover may be turned by pushing or pulling slightly on the article or pipe supporting ornamental parts 33 which are secured to the cover by screws 34, as shown in Figs. 2 and 3. The upper end portions of the ornamental 15 parts do not touch the standard 17.

While the invention has been described in detail and many modifications and specific applications thereof have been referred to, the invention herein is not limited to such specific applications 25 and it is intended that all matter shown in the accompanying drawing and particularly described in detail shall be interpreted as illustrative and not in a limiting sense.

What is claimed is:

1. An electric lamp structure comprising a hollow base including a vertically arranged annular rim, an annular table rotatable relative to said rim and having an outer marginal portion disposed in superimposed relation to said rim, 35 said table including an inner annular portion, a gear depending from said inner annular portion, a fixed closure for said table and seated on said inner annular portion, a depending support carried by said closure and disposed within said rim, a cable receiving vertical standard sustained by said closure, and a make and break switch carried by said depending support and having a rotatable member including gear means in mesh with said gear. 40

2. An electric lamp structure comprising a hollow base including a vertically arranged annular rim, an annular table rotatable relative to said rim and having an outer marginal portion disposed in superimposed relation to said rim, 50 said table including an inner annular depressed portion, a gear depending from said depressed portion, a fixed closure for said table and seated on said depressed portion, a depending support carried by said closure and disposed within said 55

rim, a cable receiving vertical standard sustained by said closure, and a make and break switch carried by said depending support and having a rotatable member including gear means in mesh with said gear.

3. An electric lamp structure comprising a hollow base including a vertically arranged annular outer rim, an annular table rotatable relative to said rim and having an outer marginal portion disposed in superimposed relation and in close proximity to said rim, said table including an inner annular depressed portion, a gear depending from said depressed portion, a closure for said table and seated on said depressed portion, a depending support carried by said closure and disposed within said rim, a cable receiving standard sustained by said closure, a make and break switch carried by said depending support and having a rotatable member including gear means in mesh with said gear, and adjustable means for fixedly holding said closure to said depressed portion.

4. An electric lamp structure comprising a hollow base including a vertically arranged annular rim, an annular table rotatable relative to said rim and having an outer marginal portion disposed in superimposed relation to said rim, said table including an inner annular depressed portion, a curved gear depending from said depressed portion, a closure for said table and having a marginal part seated on said depressed portion, a depending support carried by

said closure and disposed within said rim, a cable receiving member extending above said base and secured to said closure, a make and break switch carried by said depending support and having a rotatable member including gear means in mesh with said gear, and means for holding said marginal part seated against said depressed portion.

5. An electric lamp structure comprising a hollow base including a vertically arranged annular rim, a substantially rectilinear annular table rotatable relative to said rim and having an outer marginal portion disposed in superimposed relation and in close proximity to said rim, said table including an inner annular depressed portion, an annular gear depending from said depressed portion, a dome shaped closure for said table and having an outer marginal part seated on said depressed portion, a depending support carried by said closure and disposed within said rim, a cable receiving hollow standard rising above said base and secured to said closure, a make and break switch carried by said depending support and having a rotatable member including gear means in mesh with said gear, lugs depending from said dome and extending within said base, sockets carried by said base for receiving said lugs, and adjustable means in part within said sockets and cooperating with said lugs to securely hold said marginal part against said depressed portion.
